UNITED STATES PATENT OFFICE.

JOHN S. BARNES, OF DETROIT, MICHIGAN.

PROCESS OF MAKING METALLIC FABRIC.

1,282,171.

Specification of Letters Patent. Patented Oct. 22, 1918.

Application filed January 8, 1917. Serial No. 141,149.

To all whom it may concern:

Be it known that I, JOHN S. BARNES, a citizen of the United States of America, residing at Detroit, in the county of Wayne 5 and State of Michigan, have invented certain new and useful Improvements in Processes of Making Metallic Fabric, of which the following is a specification, reference being had therein to the accompanying 10 drawings.

This invention relates to a wire fabric weaving machine especially designed for producing interwoven wire fabric that can be used for fences, gates, trellises, gratings, 15 baskets and various foraminous structures.

My invention aims to provide a weaving machine by which strands of wire may be economically and expeditiously interwoven, in a manner as hereinafter set forth, to 20 form a foraminous fabric having uniform interstices and the interwoven strands interlocked against accidental displacement. The wire fabric produced by the machine necessarily involves a process of manufac- 25 ture, and the first step consists in cutting a piece of wire into desired lengths and notching each piece of wire. This step of the process is accomplished by a novel punching machine into which the pieces of 30

wire are automatically moved and opposed walls thereof provided with alternate or staggeredly arranged notches. The spacing of the notches and the cross sectional area of the same determine the weave of the 35 fabric and the size of the interstices thereof. The second step involved in weaving the fabric consists in utilizing a pressing machine for holding and correctly positioning the pieces of wire whereby weaving opera- 40 tions may be conveniently and continuously carried on by an attendant of the machine. This step of the process calls for an especially designed pressing machine that will hold pieces of wire in proper relation where- 45 by other pieces of wire may be expeditiously placed in position to be interwoven.

The third step involved in the process of weaving consists in bending the pieces of wire held in the pressing machine whereby 50 other pieces of wire may be placed in position to be interwoven. The bending of the pieces of wire held in the machine is of utmost importance as it determines the nature of the weave and more so than any

other step it contributes to the perfection 55 of the fabric. To bend unwoven ends of strands of wire held by the machine it is necessary to use coöperating members and the design of these members is determined and governed by the spacing of the notches 60 produced by the first step of the process.

The fourth step involved in the fabrication is that of pressing home or correctly positioning pieces of wire whereby they become interlocked at their intersection, and 65 this step is accomplished in connection with the weaving machine.

Associated with the above steps are cer- 70 tain minor steps and results that produce a novel article of manufacture in the form of a woven fabric having all the interwoven strands in a common plane. This is accom- 75 plished by interlocking the pieces or strands of wire at the notches thereof and after the pieces or strands of wire are pressed into position it is practically im- 80 possible for the same to become accidentally displaced. A rigid and durable fabric is produced which may be used for various purposes, and considerable importance is attached to the rapidity at which heavy 85 pieces or strands of wire may be accurately interwoven.

The various steps involved in the produc- 85 tion of the fabric will be better understood as the construction of the machine is de- 90 scribed; therefore reference will now be had to the drawings, wherein—

Figure 1 is a front elevation of a weaving machine, partly broken away;

Fig. 2 is a vertical sectional view of the same, partly broken away;

Fig. 3 is a perspective view of a portion of the machine illustrating the wire bending and interlocking members;

Fig. 4 is a cross sectional view of the machine, taken on or about the line IV—IV of Fig. 1;

Fig. 5 is a plan of a portion of the ma- 100 chine;

Fig. 6 is a perspective view of a piece of notched wire;

Fig. 7 is a similar view of a piece of wire fabric;

Fig. 8 is a perspective view of a portion 10 of the machine, illustrating spacing devices;

Fig. 9 is a plan of a punching or notch- 105 ing machine, partly in section;

Fig. 10 is an elevation of the machine partially broken away and in section;

Fig. 11 is a sectional view taken on the line XI—XI of Fig. 9,

Fig. 12 is a cross sectional view on the line XII—XII of Fig. 9, and

Fig. 13 is a cross section of a set of rolls constituting means for subjecting woven fabric to pressure whereby the woven strands thereof are in a common plane.

In describing my invention by aid of the views above referred to, I desire to point out that the same are intended as merely illustrative of an example of machines by which the process of manufacturing wire fabric may be carried into effect; therefore I do not care to limit my invention to the precise construction and arrangement of parts shown. The following description is therefore to be broadly construed as including substitute constructions and arrangement of parts which are the mechanical equivalent of those hereinafter referred to.

The first step involved in the manufacture of wire fabric is accomplished by a cutting or notching machine, and the essential part of such a machine has been illustrated in Figs. 9 to 12 inclusive.

The reference numeral 1 denotes a stationary die or head block having a transverse opening 2 adapted to receive a piece of wire 3 which has been previously cut a desired length. The die or head block 1 is preferably made with an interexchangeable member 4 provided with grooves 5 having the lower ends thereof in communication with the discharge openings 6 in other members of the die or head block.

Slidable in the grooves 5 are parallel punches 7 carried by a head 8 connected to a vertical reciprocable member 9, said member representing the punching head of an ordinary machine. The grooves 5 are at opposite sides of the opening 2 which intersects said grooves and said grooves are at the ends of the opening of the member 4, thereby exposing spaced portions of the piece of wire 3 in the grooves 5 of the die or head block, whereby the punches 7 may cut or punch opposed walls of the piece of wire 3 and discharge the punchings through the openings 6. It is therefore essential that the punches 7 be set at opposite sides of the central longitudinal plane of the die or head block 1, as best shown in Fig. 9, and by simply changing the member 4 of said block and the punches 7 of the reciprocable member 9, a piece of wire 3 may be provided with notches spaced as desired.

A piece of notched wire is shown in Fig. 6 and it will be observed that the notches 10 are in staggered relation and approximately one-half the cross-sectional area of the piece of wire. The depth of the notches 11 is essential in order that woven or inter-

locked pieces of wire will be in a common plane and this feature of my invention will be hereinafter referred to.

Suitably connected to the die or head block 1 is a horizontally disposed table 11 provided with a longitudinal slot 12 and a front wall 13. The front wall 13 has a longitudinal shoulder 14 on which the piece of wire 3 is intermittently moved and firmly held, particularly during the punching or notching operation. Adjustable in the slot 12 of the table 11 is a holder 15 for a spring pressed beveled detent 16 adapted to engage in a notch 10 of the piece of wire to hold the same against accidental movement. The detent holder 15 can be adjusted upon the table 11 and fixed relative to said table by a bolt 17 and a nut 18 or similar clamping means.

Slidable in the slot 12 of the table 11 is a feeding member 19 having a spring pressed beveled dog 20 to engage in a notch of the piece of wire and move or advance the piece of wire upon the table when the member 19 is moved in one direction. When moved in the opposite direction the dog 20 recedes to obtain a fresh grip on the piece of wire and the spring pressed detent 16 will hold the piece of wire while the feeding member 19 recedes. The detent 16 is only employed for holding the piece of wire during the interim in which the punches 7 are not in engagement with the piece of wire. The top of the feeding member 19 has a set of apertured lugs 21 pivotally connected to a link 22 which is also pivotally connected to a lever 23 extending through the slot 12 and pivoted or fulcrumed between depending bearings 24 of the table 11. The lower end of the lever 23 is pivotally connected to a link 25 and said link is pivotally connected to a crank 26 on the end of a rock shaft 27, journaled in a depending bearing 28 of the table 11. The rock shaft 27 has another crank 29 pivotally connected to a two-part rod 30 held in an upright position by a side extension 31 of the reciprocable member 9. The upper end of the rod 30 is screwthreaded to receive nuts 32 and 33, the former being above the extension 31 and the latter below said extension. As the reciprocable member 9 descends, the extension 31 thereof impinges the nut 33 and imparts movement to the rod 30, cranks 29 and 26, lever 23, links 22 and 25, and thereby moves the feeding member 19 toward the die or head block 1, allowing the dog 20 to engage in another notch of the piece of wire 3. On an upstroke of the reciprocable member 9, it is necessary that the punches 7 reach a position above the opening 2 of the member 4 before the piece of wire 3 is advanced; therefore the clearance between the side extension 31 and the nuts 32 and 33. Immediately upon the punches 7 being raised above the

opening 2 of the member 4, the side extension 31 impinges the nut 32 and the rod 30 is elevated and the feeding member 19 shifted away from the die or head block 1 to 5 move the piece of wire 3 a predetermined distance to be notched by the punches 7.

The machine just described constitutes means for notching pieces of wire, and reference will now be had to Figs. 1 to 5 inclusive and Fig. 8, showing the machine by 10 which the second, third and fourth steps of the process of manufacturing wire fabric are carried into effect.

The machine comprises a stationary frame 15 generally denoted A and a fulcrumed or pivoted frame generally denoted B. The frame A has a base 40 and in elevation, the frame conforms somewhat in shape to an A frame, that is, it has legs 41, transverse braces 42 and 43 and angularly disposed converging arms 44 with the apex thereof connected to a ceiling bracket or hanger 45.

The fulcrumed or pivoted frame B rests upon the base 40 in front of the stationary 25 frame and in front elevation conforms to the shape of said stationary frame. The legs of the fulcrumed frame are designated 46, the arms are designated 47 and a brace is designated 48.

30 In front of the apex of the frame B is a ceiling bracket or hanger 49 having bearings 50 cooperating with bearings 51 on the stationary frame in supporting cam shafts 52 in front of the arms 47 of the fulcrumed 35 frame. The cam shafts 52, contiguous to the bearings thereof, have cams 53 engaging the fulcrumed frame B to move said frame toward the stationary frame A. Intermediate the ends of the cam shafts 52 are cranks 40 or levers 54 which permit of attendants or operators of the machine rocking said shafts to swing the fulcrumed frame to a closed position. The legs 46 of the fulcrum frame are prevented from becoming accidentally 45 displaced by forwardly projecting guide members 55 carried by the brace 42 of the stationary frame A, and tending to hold the fulcrum frame normally in an open position are coiled compression springs 56 in pockets 50 57 of the legs 41 of the frame A. To limit the closing movement of the fulcrum frame B the base 40 has adjustable screws or stops 58 which will correctly position the fulcrumed ends of the links 46 relative to the 55 stationary frame A.

The angularly disposed arms 44 and 47 of the frames A and B respectively are channel shaped, as best shown in Figs. 3 and 4 and the upper flanges 80 and 81 of said arms are 60 provided with detachable bending members 82 and 83 respectively. Each of these members has rigid equally spaced teeth or projections 84 and when said members are mounted upon the flanges 80 and 81 the 65 teeth of one member are staggered relative

to the teeth of the other member. The teeth 84 of said bending members overhang longitudinally recessed confronting walls 85 of the channel arms 44 and 47, and by reference to Fig. 4, it will be observed that the teeth 70 84 are of sufficient length to engage and bend pieces or strands of wire clamped between the arms 44 and 47 when the frame B is in a closed position relative to the stationary frame A. This bending of the pieces 75 of wire is facilitated by the recessed walls 85 of the channel arms and with the teeth 84 in staggered relation, the pieces of wires are bent in two directions, alternating wires 80 toward the fulcrum frame B and the remaining wires toward the stationary frame A. Such bending places one group of wires in one plane and the other group of wires in another plane, producing a V-shaped formation 85 when viewed from either end of an arm.

Considering Fig. 1, it will be observed that the arms of each frame are at right angles to each other, and that pieces of wire are shown as held between the arms of said frames with said pieces of wires in two 90 groups, one at right angles to the other, with unwoven ends protruding upwardly at right angles to the arms of the frame. This may be better understood by considering one of the frames as having one group of wires in 95 parallelism with one arm thereof and the other group of wires in parallelism with the other arm of the same frame, consequently any fabric woven in this particular machine has diagonally disposed or bias 100 strands.

By again referring to Fig. 3, it will be observed that by bending the upper ends of the pieces of strands of wire into two groups of V-shape formation, additional pieces or 105 strands of wire can be placed in position to be woven into the fabric. This is accomplished by attendants or operators of the machine and after the pieces or strands of wire are forced between the groups of wires 1 as far as possible, by hand, then interlocking members are brought into action to properly seat and position the inserted wires. These interlocking members are carried by the arms 44 of the stationary frame A and each 1 arm has bearings 86 for a trunnion bar 87 provided with spaced rigid fingers 59. The bar 87 has a handle or lever 88 at an end thereof whereby the fingers 59 of said bar can be swung downwardly on to the inserted 1 piece of wire to force the same into position and to hold the fingers normally elevated; the bar 87 has a side extension 61 connected by coiled retractile spring 62 to the arm of the frame A.

Again considering Fig. 1 in connection with Figs. 2 and 8, it will now be described how a fabric is started in the machine, shifted therein, and held therein when the frame B is in an open position. This is accom-

plished by weaving or starting a piece of fabric by hand or any other suitable means and then placing the started piece of fabric in the machine. To hold it therein and permit of its movement during the weaving operation, novel spacing devices are employed in connection with the frame B.

The fulcrumed frame B has a longitudinally slotted support 65, above the brace 48 thereof, and adjustable on this support, are brackets 66 supporting housings 67. The top and bottom of each housing has a longitudinal slot, and reciprocable in the housing are slide members 68 and 69, one above the other. The slide members 68 and 69 of each housing have apertured lugs 70 extending through the slots of the housing and connected by links 71 to a cross head or double crank 72 slidable upon a shaft 73, but adapted for rocking with said shaft through the medium of splines engaging in the grooves 74 of said shaft. Intermediate the ends of the shaft is a lever 75 which has the lower end thereof connected by a coiled retractile spring 76 to the support 65. It is by virtue of the lever 75 that the members 68 and 69 can be reciprocated in the housings 67, and said members are provided with pins 77 adapted to engage in the meshes or interstices of the woven fabric and support said fabric, particularly when the fulcrum frame B is in an open position. The elements 66 to 77 inclusive constitute spacing devices, and by referring to Fig. 8, it will be observed that the pin 77 of the slide member 69 supports the fabric by engaging under strands of wire, at their intersection, so that the fabric is suspended from said pin. The pin 77 of the slide member 68 is in position to enter the mesh or interstice of the fabric above the pin of the slide member 69, and when said slide member is shifted to a retracted position by rocking the shaft 73, the pin of the slide member 68 moves forward into the fabric and supports the same similar to the pin of the slide member 69. During this shifting of the slide members 68 and 69, the woven fabric has descended by gravity and the intermittent movement of the fabric is determined by reciprocating the slide members. The spacing devices are operated in synchronism by the lever 75 and said devices allow the woven fabric to intermittently move in the machine, and to guide the fabric from the machine, the brace 48 of the fulcrum frame B has curved skid or slide ways 78, as best shown in Fig. 2.

In the operation of the weaving machine, it is preferable to have two operators, although it is possible to operate the machine with a single operator. Assuming that a piece of fabric has been started in the machine and that it is clamped between the arms 44 and 47 of the frames A and B, the

fabric is held until each operator inserts a piece or strand of previously notched wire between the groups of wire protruding from the arms of the frames. As the protruding ends of the wires have been previously notched in the punching machine and properly started in the weaving machine, the notches of said wires are in a plane confronting any of the notches of the inserted wires, and as shown in Fig. 1, it is only necessary for the operators when inserting these wires to match notches or interlock one end of the inserted wire with one of the protruding wires, as generally designated at C, thus properly positioning the notches of the inserted wire relative to the groups of wires protruding from the machine. Assuming further that the inserted wire has been forced home as far as possible, by hand, the operator of the machine manipulates the lever 88 to swing the fingers 59 of the interlocking members on to the inserted wires, to further force said wires between the groups of protruding wires, as shown in Figs. 3 and 4, thus interlocking the notched or recessed confronting walls of the contacting wires. This step in the process of manufacturing the fabric having been performed, the operators of the machine now rock the cam shafts 52 and release the fulcrum frame B relative to the stationary frame A, thus throwing the weight of the upper part of the fabric upon a pin 77 of each spacing device. An operator now rocks the shaft 73 and the spacing devices are actuated in synchronism. The pins 77 supporting the fabric are withdrawn therefrom to allow the fabric to descend on to and be supported by the other pins of the spacing devices, and in consequence of this operation the fabric has been lowered between the frames A and B.

The wires previously inserted are carried to a position between the channel arms 44 and 47 of said frames and when the frame 47 is closed by the cams 53, the interlocked wires are pressed between the arms 44 and 47 to such an extent that the walls of the notches 10 are brought into snug engagement thus precluding any danger of the interlocked wires becoming accidentally displaced.

Simultaneous with the clamping of the wires between the arms 44 and 47, the bending members 82 and 83 are brought into action to bend the protruding ends of the wires whereby the wires may be inserted as previously described.

The fabric woven by the machine has the pieces or strands of wire thereof interlocked by the rigidity of the wire, by the weave of the fabric, and by pressure brought to bear between the frames A and B, and as a precautionary measure, I may further subject the woven fabric to the action of rolls 79

shown in Fig. 13. These rolls will positively move all the strands of the wires into a common plane, and in some instances, the strands of wire, at their intersection, may be further secured by spelter, welding, upsetting edges of the notches 10 and otherwise forming a positive connection between the wires, thus assuring a rigid and uniform, metallic fabrication.

10 I desire to call attention to the fact that the first steps of the process of preparing the wire for weaving purposes, may be reversed. For instance, the wire taken from a bundle may be straightened, punched, and 15 then cut into desired length, and in some instances the punching and cutting of the wire into desired length may be simultaneously performed.

What I claim is:—

20 1. A process of making wire fabric consisting of placing wires in parallel relation, simultaneously holding said wires and bending ends thereof into two groups, placing a wire between the groups of wires, forcing the placed wire into interlocked engagement with said parallel wires, and then bringing pressure to bear on the bent ends of said wires to place all of said wires in a common plane.

25 2. A process of making wire fabric consisting of placing wires in parallel relation, bending alternate ends of said wires into two groups, placing a wire between the groups of wires, and then bringing pressure to bear on said wires to force said wires into interlocked engagement in a common plane.

30 3. A process of making wire fabric consisting of placing wires in parallel relation, bending ends of said wires, placing wires between the bent ends of said parallel wires, intermittently moving all of said wires, and bringing pressure to bear upon the bent portions of said wires during an interim of movement of said wires.

35 4. A process of making wire fabric consisting of simultaneously clamping parallel notched wires and bending ends thereof, inserting notched wires between the bent ends until the notches of the inserted wires interlock with the notches of the bent ends of said wires, and then shifting all of said wires and bringing pressure to bear on the bent portions of said wires whereby said fabric is again clamped for a repeated operation.

40 5. The process of making wire fabric consisting of notching pieces of wire, holding the pieces of wire with their notched portions in contact, bending the parallel ends of the held pieces of wire, inserting and positioning pieces of wire between the parallel ends of the contacting wires, and then shift-

ing and again holding the wires with pressure brought to bear on the notched contacting portions of the wire.

6. A process of making wire fabric consisting of cutting lengths of wire and notching walls of each wire, weaving the pieces of wire with the notched portions thereof contacting, holding the woven wires and bending protruding ends thereof, inserting pieces of wire between the protruding ends of woven wire, pressing the inserted wires until the notched portions thereof interlock with the notched portions of the protruding ends of woven wires, moving the bent portions of said woven wires, and then bringing pressure to bear against said woven wires.

7. A process of making wire fabric consisting of cutting lengths of wire and notching walls of each wire, weaving the pieces of wire with the notched portions thereof in contact, simultaneously bringing pressure to bear upon the contacting notched portions of said wires and bending the protruding ends thereof, inserting pieces of wire between the protruding ends of woven wire, pressing the inserted wires until the notched portions thereof interlock with the notched portions of the protruding ends of woven wires, and shifting the woven wires and then bringing pressure to bear on the bent wires.

8. A process of making wire fabric consisting of notching pieces of wire, holding the pieces of wire between frames with the notched portions thereof in contact, bending protruding ends of the held pieces of wire by bending members on said frames, inserting pieces of wire between the protruding ends of said wires, and then locking said inserted wires in engagement with the first mentioned wires by interlocking members on said frame.

9. A process of making wire fabric consisting in simultaneously clamping previously woven wire fabric and bending unwoven ends of the wire, inserting additional wires between the bent ends of said wires, and then shifting and again clamping the fabric to interlock the wires by pressure.

10. A process of making wire fabric consisting in placing groups of wires in angularly disposed relation, placing wires between the groups of wires, and then bringing pressure to bear on all of said wires to force said wires into interlocked engagement in a common plane.

In testimony whereof I affix my signature in presence of two witnesses.

JOHN S. BARNES.
